[57] **CLAIM**

The ornamental design for a food dislodger for performing the Heimlich maneuver, as shown and designed.

DESCRIPTION

FIG. 1 is a top perspective view of a food dislodger for performing the Heimlich maneuver, showing our new design;

FIG. 2 is a side elevational view thereof;

FIG. 3 is a bottom perspective view thereof;

FIG. 4 is a side elevational view thereof, opposite that shown in FIG. 1;

FIG. 5 is a front elevational view thereof; and,

FIG. 6 is a rear elevational view thereof.
